CLAIM

The ornamental design for a sample reader, as shown and described.

DESCRIPTION

FIG. 1 is a front perspective view of a sample reader showing our design.

FIG. 2 is a front side elevational view thereof.

FIG. 3 is a rear side elevational view thereof.

FIG. 4 is a right side elevational view thereof.

FIG. 5 is a left side elevational view thereof.

FIG. 6 is a top plan view thereof.

FIG. 7 is a bottom plan view thereof; and,

FIG. 8 is a bottom perspective view thereof.

In FIG. 6, the broken lines show portions of the sample reader that form no part of the claimed design.
